AUTOTRANSFORMER FOR ALTERNATING CURRENT HAVING VARIABLE TRANSFORMATION RATIOS

Application filed April 18, 1927, Serial No. 184,735, and in Italy April 22, 1926.

This invention relates to auto-transformers, having variable transformation ratios, for alternating current, and has for its object an improved transformer of this character. According to the principal feature of the invention an auto-transformer is provided with four windings connected electrically in series and arranged individually in pairs on magnetic cores in such a manner as to generate interlinked magnetic fluxes therein, the two inner windings which constitute one of the pairs, being arranged to generate magnetic fluxes of equal magnitudes acting in opposite directions, and the two outer windings, constituting the other pair, being arranged to generate fluxes of equal magnitudes acting in the same direction, when a current traverses the four windings in series, means being provided for the relative orientation of the magnetic fluxes generated by the two pairs of windings, with the object of varying the difference of potential between the middle point of the series of windings and the two terminals of the series.

A further feature of the invention consists in the application of an auto-transformer of the kind described above to the various current tappings of an ordinary transformer for the supply of an alternating current line with the object of regulating the working tension of the line.

The invention is illustrated diagrammatically and by way of example only, in the accompanying drawing in which:—Figures 1 and 2 are transverse and longitudinal sectional views respectively of the improved auto-transformer. Figure 3 a circuit diagram thereof. Figure 4 an equivalent circuit diagram, and Figures 5 and 6 are views illustrating the application of the auto-transformer to the regulation of the working tension of a line supplied by an ordinary transformer.

Referring first to Figures 1 and 2 of the drawing, the auto-transformer comprises

two magnetic cores 1, 2 built up of iron laminæ, in which suitable recesses are provided for accommodating the various windings. The magnetic cores which are separated from one another by a small air-gap, 50 are rotatable with respect to one another, for example the core 1 is the stator (as illustrated in the drawing), being integral with the body portion 5, and the core 2 is the rotor, being integral with a shaft 2' rotatably mounted in 55 bearings 3, 4 of the body portion 5. The rotor may be rotated directly by hand or mechanically by means of a worm 6 adapted to engage with a worm wheel 7 secured to the shaft 2'. The windings (Figures 1, 2, 3) 60 are four in number, I, II, III, and IV, and are connected together in series, preferably an equal number of turns being provided in each winding. The windings I and IV are integral with the stator and the windings 65 II, III are integral with the rotor. The terminals —a, g— of the series of windings are connected to two wire clamps X, Z, the middle point —d— of the series, being connected to wire clamp Y. The windings I and IV, 70 when a current traverses them, generate a flux interlinked with the rotor in the fixed direction N, N. When a current from X to Z or vice versa traverses the windings I and IV, in the same direction, the combined action of the windings is to generate two equal fluxes resulting in a single resultant flux, but, if on the contrary the current traverses the windings I and IV in opposite directions and converges and leaves at the middle point 75 —d—, the combined action of the two windings is such as to generate two opposite fluxes resulting in a flux which is equal to the difference between the fluxes generated by each of the windings I and IV. The windings II and 80 III are arranged in such a manner that each generates a flux in the direction M, M of the rotor and interlinked with the stator. The combined action of the windings II, and III 85 when they are traversed by a single current 90

in the same direction, is to generate equal and opposite fluxes, and when they are traversed by the current in different directions, to generate fluxes in the same direction which 5 combine to form a single resultant flux. In other words the windings I and IV are wound in the same direction, whilst the windings II and III are wound in a direction opposite to one another.

- 10 The rotor 2 may be rotated from the position in which it is illustrated in Figure 1 through an angle α (Figure 3) so that the direction M, M of the field generated by the rotor windings is inclined at an angle α to the direction N, N of the field generated by the windings of the stator. In this case the 15 alternating field in the direction M, M has two orthogonal components, one in the direction N, N and the other at right angles to this direction, and in transformers of a certain power it is advisable to eliminate the component at right angles to the direction N, N by means of a short circuited winding W of 20 low ohmic resistance arranged on the stator 25 (Figure 1).

In practice, if the rotor is not rotated through an angle greater than one complete turn in either direction from the middle position, the connections —b, c— and —e, f— 30 between the circuits of the stator and rotor, and also between the middle point —d— and the wire clamp Y, may be effected through flexible conductors, but there is no reason why these connections should not be made through friction contacts with the object of increasing the range of operation. Thus, as shown in Figure 2, the terminals of the windings of the rotor and the middle point of these windings are connected respectively to rings —c, 35 —e, d— integral with the shaft 2' of the rotor, the brushes —b, f— making contact with the rings —c, e— being connected to the internal ends of the circuits I and IV, and a brush —d'— making contact with the ring —d—, 40 being connected to the wire clamp Y.

The action of the transformer is as follows—

Assume that the rotor (Figure 3) has been rotated through an angle α from its normal 50 position in which it is illustrated in Figure 1 and that an alternating flux ϕ , generated by a difference of alternating potential V impressed at the ends X, Z of the series of windings, is established in the direction N, N; then if S is the number of the turns in each winding, in the winding I there will be S turns linked with the flux $+\phi$. In the winding II there will be S turns linked with the component $-\phi \cos \alpha$ of this flux, or its equivalent $-S \cos \alpha$ turns linked with the flux $+\phi$. In the winding III there will be S turns linked with the flux $+\phi$ and in the winding IV, S turns linked with the flux $+\phi$. The equivalent circuit is illustrated in Figure 4, that is to say an auto-

transformer the total number of turns of which is 2S and in which the position of the wire clamp Y is as $S \cos \alpha$ turns from the middle of the winding. The turns of the two circuits of this auto-transformer would therefore be respectively $S(1 + \cos \alpha)$ and $2S$, and consequently the ratio of transformation is

$$\frac{V'}{V} = \frac{1 + \cos \alpha}{2}, \quad 75$$

this ratio varying from one to zero when α varies from zero to π .

Figure 5 illustrates the application of an auto-transformer of the kind described above 80 for regulating the tension in the line 8, 8' supplied for example by the secondary 9 of a transformer. With the object of regulating the tension of a line the secondary 9 has been provided previously with a number of 85 tappings $n-2, n-1, n, n+1$ etc., at various points in the secondary of the transformer, the line wire 8' being arranged to be connected to any of these tappings to increase or diminish the working tension of the line. 90 It is however a difficult matter to effect connection of the line wire 8' with the various tappings, when the whole system is under load and comparatively great currents are to be dealt with, commutators immersed in oil having to be employed for this purpose. Moreover the tension is not regulated in a continuous manner by such an arrangement but in steps corresponding to the difference 95 of potential between the various tappings. When employing an auto-transformer constructed in accordance with the present invention, the wire clamps X, Z are connected to two successive tappings, the wire clamp Y being connected to the line wire 8'. In certain 100 circumstances the secondary winding consists of two portions 9, 9' (see Fig. 6), the tappings being arranged toward the middle of the secondary winding, that is to say, at the internal end of one of the two portions 105 of the winding, and when this is the case the wire clamp Y is connected to the internal extremity 9' of the portion 9' of the winding not comprising the tappings, while the external extremities 9^x, 9^y of the two portions 110 of the winding are connected to the line wires 8 and 8'. Thus for an angle α equal to zero, the fields generated by the windings I, II eliminate one another, those generated by windings III, IV being additive. The reactance offered to the passage of a current $-i'$ between X and Z is at a minimum, but that offered to the passage of a current $-i''$ between Z and Y is comparatively great, and consequently $-i''$ will be zero, 115 and only a small magnetization current will pass; the potential of wire clamp Y will be substantially equal to that of the tapping $n-1$ and consequently of wire clamp X. Upon making α equal to π the fields generated 120

115

120

125

130

5 by windings I and II will be additive and those due to windings III and IV will eliminate one another; the reactance offered to the passage of the current $-i''$ is therefore negligible, that offered to the passage of the current $-i'$ being comparatively great, so that the potential of wire clamp Y will be substantially that of the tapping $-n$ and consequently of Z. Therefore by varying α 10 from zero to π the value of the tension of line can be varied in a continuous manner between the values of the potential of the tappings $n-1$ and n . Moreover when it is desired to disconnect from one tapping and 15 to connect to the succeeding tapping, the rotor is placed in a position, in which α is equal to zero or to π , so that the whole of the current will pass across the tapping which remains connected, only the magnetization 20 current therefore passing through the tapping which is about to be connected or disconnected. Simplicity of operation, without any danger, is thus attained and commutations may thus be effected by means of an 25 ordinary controller no special commutators immersed in oil which are very expensive and cumbersome being necessary.

It will be evident that the invention is not limited to the particular arrangements hereinabove described which may be varied, as 30 desired to suit particular requirements.

I claim:

1. An auto-transformer having variable 35 transformation ratios, comprising four windings electrically connected in series, a core for the pair of intermediate windings and a core for the pair of outer windings of the series, the windings of the intermediate pair of windings arranged to generate equal and 40 opposite fluxes and the windings of the external pair being arranged to generate equal fluxes in the same direction when the current traverses all four windings in series, and means for varying the relative orientation of 45 the magnetic fluxes generated by the two pairs of windings to vary the difference of potential between the middle point of the series connected windings and the two terminals thereof.

50 2. An auto-transformer having variable transformation ratios, comprising four windings connected in series, two relatively movable cores, the intermediate windings distributed on one core and the extreme windings 55 distributed on the other core, and means to relatively move the cores to vary the orientation of the magnetic fluxes generated by the two pairs of windings.

3. An auto-transformer having variable 60 transformation ratios, comprising four windings electrically connected in series, two magnetic relatively movable cores, the intermediate windings arranged on one core and the extreme windings arranged on the other core, a 65 short circuited winding of low ohmic resist-

ance on one of the cores at right angles to the windings thereon to oppose any variation of flux in the other core in a direction at right angles to the flux generated by the windings mounted on the first core.

4. The combination with a stationary alternating current transformer having a set of taps; of an auto-transformer having two cores, two windings on each core, all the windings being connected in series, and one of the cores rotatable with respect to the other, the intermediate windings being wound in opposite directions and their middle point arranged for connection to a service line and the external windings connected between two 80 taps of the stationary transformer.

5. The combination with a stationary alternating current transformer having a portion with an intermediate set of taps and another portion without taps; of an auto-transformer having two cores, two windings on each core, all the windings being connected in series, and one of the cores rotatable with respect to the other, the intermediate windings being wound in opposite directions and their middle point connected to the line through an invariable portion of the winding of the stationary transformer and the external windings connected between two taps of said stationary transformer.

In testimony that I claim the foregoing as my invention, I have signed my name.
